UNITED STATES PATENT OFFICE.

STEFAN AUGUST SCHOLZ, OF TSCHIRNAU, GERMANY.

PEN-HOLDER.

SPECIFICATION forming part of Letters Patent No. 425,583, dated April 15, 1890.

Application filed August 17, 1889. Serial No. 321,170. (No model.)

To all whom it may concern:

Be it known that I, STEFAN AUGUST SCHOLZ, a subject of the Emperor of Germany, residing at Tschirnau, in the Empire of Germany, have 5 invented a new and useful Pen-Holder, of which the following is a specification.

My invention relates to improvements in pen-holders, and has for its purpose to facilitate the removal of the pen from the holder, 10 thereby obviating the inconveniences and dangers attendant on the extraction of pens from the holders hitherto employed.

In the accompanying drawings, Figure 1 is the front view of the pen-holder; Figs. 2 and 15 3 are vertical and longitudinal sections, and Fig. 4 is a side view of the pen-holder.

The improved pen-holder essentially consists of a cylindric body or core A, contained in a tube C, extending from its rear extremity 20 to an arched cavity or saddle a, provided on its fore end for receiving the pen. From said saddle a projects a pin a', rounded at the top and held up by the action of a suitable spring a², lodged in a corresponding cavity diametrically provided in the core A of the holder. The front part of the core A is inclosed in a small tube B, telescopically movable within the main tube C, and held in position by aid of a spiral spring b, surrounding a thinner or cylindrically recessed portion of the core A. By shift-

ing the small tube B into the main tube C the pen-saddle a is laid open, and after placing the pen in its position and depressing therewith the projecting pin a' the small tube B is allowed to be propelled by the spiral spring b 35 and to cover the inner portion of the pen, which, with the assistance of the upward tendency of the depressed pin a', is thus secured in the holder; or the pen may be introduced in the usual manner, thereby depressing the pin 40 a' sufficiently to hold the pen in position.

To remove the pen from the holder the small tube B is merely shifted back, thus causing the pen to be expelled by the action of the elastic pin a'.

Having fully described my invention, what I desire to claim and secure by Letters Patent of the United States is—

The combination, in a pen-holder, of a cylindric body A, on the front part of which slides 50 the tube B, propelled by the spiral spring b, with the pin a' lodged in a diametrical cavity of the core A, pressed upward by the spring a², and projecting from the saddle or arched cavity a of the core A, as described, and for 55 the purpose specified.

STEFAN AUGUST SCHOLZ.
